(57) CLAIM

The ornamental design for a golf glove, as shown and described.

DESCRIPTION

FIG. 1 is a front top perspective view of a golf glove showing our new design.

FIG. 2 is a rear top perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The dash-dash disclaim lines in FIG. 8 mark the disclaimed portions that form no part of the claimed design. No claim is made to the interior portions of the glove.

1 Claim, 8 Drawing Sheets

FIG. 1

FIG. 2

FIG. 3

FIG. 4

FIG. 5

FIG. 6
